CONVEYER AND SWITCH MEANS FOR
CHECKOUT COUNTERS

Allan D. Foster, Detroit, Mich.

Application August 23, 1950, Serial No. 180,993

8 Claims. (Cl. 198—68)

1

The present invention pertains to a novel checkout counter for self-serve grocery stores and other establishments where merchandise is to be checked rapidly.

The conventional checkout counter is staffed by a cashier and one bagging clerk. It is a matter of experience that the cashier can ring up merchandise faster than the bagging clerk can arrange it in bags. As a result, the cashier must wait periodically for the bagging clerk to catch up. The output of each counter is thereby retarded, and the customers are required to wait longer in line. Also, the efficiency of the cashier is reduced by the necessity of pulling the goods manually to a position where she can see the price marks thereon.

The principal object of the invention is to provide a checkout counter that permits the cashier to work more steadily. This object is accomplished generally by a construction that provides a mechanically driven belt for bringing the goods to the cashier and accommodates two bagging clerks at each counter, with a device that enables the cashier to direct the merchandise to one clerk or the other.

Two bagging clerks may, however, be able to work faster than one cashier. In this connection another object of the invention is to provide means for facilitating the work of the cashier. Ordinarily she is required to pull or drag the merchandise to a point within her reach for ringing up. The invention eliminates the time and effort consumed in this operation by providing a mechanical conveyor, operated at will by the cashier, to bring the merchandise within her reach. A checkout counter constructed according to the invention has twice the output of a conventional counter, since the output is determined by the work performed at the bagging end.

In the accomplishment of these objects, the counter is fitted with a pair of endless belt conveyors arranged in line and separated from each other at the cashier's station. The conveyor between the cashier and the bagger is in constant motion during the use of the counter and carries the merchandise to the bagging end after it has been rung up. The other conveyor receives the merchandise as it is initially laid upon the counter by the customer. To bring the merchandise within her reach for ringing up, the operator depresses a pedal to operate a driving connection or other clutch for connecting the constantly running conveyor to the forward conveyor. The separation between the conveyors is bridged by a fixed smooth plate which stops each article and requires the cashier to handle it. As the articles are rung up, the cashier merely slides them across the plate to the discharge conveyor.

This conveyor carries the merchandise to a somewhat wider table which is divided by a partition into equal areas, each serviced by its own bag-

ging clerk. To this partition is hinged a deflector positioned to sweep across the discharge conveyor and adjustable by the cashier to direct the merchandise to one side or the other of the partition. Ordinarily the cashier distributes the orders alternately to the two bagging clerks.

The invention is fully disclosed by way of example in the following description and in the accompanying drawings in which:

Figure 1 is a perspective view of the device;
Figure 2 is a plan view;
Figure 3 is a section on the line 3—3 of Figure 2;
Figure 4 is a section on the line 4—4 of Figure 3;
Figure 5 is an enlarged detail of Figure 3;
Figure 6 is a section on the line 6—6 of Figure 5;
Figure 7 is a section on the line 7—7 of Figure 3;
Figure 8 is a section on the line 8—8 of Figure 3;
Figure 9 is a section on the line 9—9 of Figure 3;
Figure 10 is a perspective detail view of the

stop plate;

Figure 11 is a plan view of a modification, and
Figure 12 is a section on the line 12—12 of Figure 11.

Reference to these views will now be made by use of like characters which are employed to designate corresponding parts throughout.

The checkout counter, as shown in Figures 1 and 2, comprises an elongated rectangular frame 1 which is widened at 2 at one end and entirely at one side of the narrower portion. The exposed portion of the frame consists of a vertical wall structure 3 built on a suitable skeleton, parts of which will presently be described. On the same side of the narrower portion 1 and approximately midway between the ends thereof is mounted a separate stand 4 which supports a cash register 5. The clerk stands in the space between the stand 4 and the wider portion 2 and faces the register 5 or the free end of the section 1. The customers approach from that direction and along the opposite side of the counter. For the purpose of description, the forward end of the counter will be regarded as the end which the customers reach first, or the previously designated free end. The sections 1 and 2 are enclosed in a marginal wall 6 for confining the goods which are laid on the horizontal supporting surfaces that will presently be described.

In the forward end portion of the section 1 is mounted a pair of transverse shafts 7 in the same horizontal plane and one behind the other. The shafts carry rollers 8 over which is passed an endless belt 9. Similarly, the rearward portion of the section 1 carries a pair of transverse shafts 10 in the same horizontal plane as the shafts 7 and also one behind the other. The shafts 10 carry rollers 11 around which is passed an endless belt 12 having its upper lap in alignment with the upper lap of the belt 9. The forward roller 11

is spaced from the rearward roller 8 for a purpose that will presently be described.

The belt 12 is intended to be driven continuously while the counter is in use. For this purpose a motor 13 mounted on the framework drives a sprocket wheel 14 through a reducer 15. The forward shaft 10 carries a sprocket wheel 16 which is connected to the wheel 14 by a sprocket chain 17. The circuit for the motor is controlled by a manual switch 17' on a side of the framework at the space occupied by the clerk.

It will be seen in Figure 3 that the belt 9 is not permanently connected to the drive for the belt 12. The customer deposits his purchases upon the belt 9. This belt is driven intermittently through a mechanism controlled by the clerk in order to move the goods within reach of the clerk at her convenience.

The selective drive for the belt 9 is operated from a pedal or treadle 18 pivoted at 19 to a floor piece or base 20 lying near the stand 4 and thus within convenient reach of the clerk. Above the pedal, a portion 21 of the frame structure carries a pair of pillow blocks 22 across which is journalled a transverse shaft 23, as shown more clearly in Figure 8. The shaft 23 is crossed by a pair of arms 24 secured thereto. The forward end of one of the arms is connected to the free end of the pedal 18 by a link 25 with an inserted coil spring 26.

The forward end of each arm 24 has inserted therein a transverse stud 27 which is held frictionally and is capable of turning under pressure. At one side of the arm 24, the stud 27 is formed with a tapped head 28 (Figure 7) and receives a cotter pin 29 at the other side of the arm. In each head 28 is screwed a substantially vertical stem 30 which, after adjustment, is secured by lock nuts 31. In the upper ends of the stems is mounted an idler or roller 32 which normally lies between and spaced below the rearward roller 32 which normally lies between and spaced below the rearward roller 8 and the forward roller 11, as shown in Figure 3. It is now apparent that the belt 9 is driven, when desired, by pressure on the pedal 18 thus bringing the roller 32 into engagement with both belts at the rollers just mentioned. The belt 9 is driven in this manner to bring the goods within more convenient reach of the clerk. By proper control of the belt 9, the operator can avoid mixing the orders of successive customers. Such mixing of orders is a serious objection to a continuously moving belt between the customer and the cashier.

Between the rear roller 8 and the forward roller 11 is a transverse frame piece 33 lying somewhat below the upper laps of the belts 9 and 12. On this piece is secured a board 34, by screws 35, substantially bridging the space between the belts. Upon the board is laid a stop plate 36 held only by its downturned ends 37 which are notched at 38 to receive the piece 33. The end portions 37 are cut arcuately at 39 and the transverse edges of the plate 36 are sharpened at 40, so that the upper surface of the plate 36 is continuous with the upper surface of the upper laps of the belts.

When merchandise is carried near to the part 36 by the belt 9, the clerk should stop the belt, ring up this merchandise on the register, and slide it manually across the plate 36 to the constantly moving belt 12. However, if she does not stop the belt 9 quickly enough, the merchandise

will be moved onto the plate 36 and will remain there since this plate is not in motion, thus providing a positive check on each item and allowing the clerk somewhat more time to ring up the merchandise. A fairly competent clerk will not delay so long as to permit more oncoming merchandise to move articles from the plate 36 onto the belt 12.

The wider section 1 of the counter is provided with a floor 41 hinged at its forward transverse edge to a frame member 42 by means of a piano hinge 43. The floor may be supported by a transverse frame piece 44 (Figure 3) in a plane sloping downward from the hinge 43. However, it may also be supported in a horizontal position by means of a latch 45 carried by and receivable in an aperture 46 in the rear end of the wall 2. This part of the wall has a number of openings 47 to receive paper bags. At this part of the wall is also mounted an external shelf 48 to support bags while being filled. The floor is adjusted to horizontal position when the cashier is not busy and has enough time to do the bagging.

Upon the floor 41 is secured a partition or divider 49, extending generally in the lengthwise direction of the counter. The forward end of the divider lies between the projections of the longitudinal edges of the narrower section 1, so that the section 2 may receive merchandise at either side of the divider. The angle of divider is such as to divide the floor 41 into substantially equal areas.

To the forward end of the divider is hingedly attached a deflector 50 adapted to sweep across the belt 12 and of such length that its free end may lie at one or the other of the stop plate 36, as shown in Figure 2. The connecting structure includes a U-shaped member 51 engaging opposite vertical sides of the divider 49 and attached thereto by a pivot pin 52. The back of the member 51 carries upper and lower angle brackets 53 (Figure 5) which overlap similar brackets 54 on the rear end of the deflector. The brackets 53 are joined to the brackets 54 by vertical pivot pins 55 which constitute the previously mentioned hinge connection. The pivot pin 52 accommodates the raising and lowering of the divider 49 with the floor 41 as described.

In the normal operation of the apparatus, two bagging clerks are stationed at the end of the shelf 48. Each bagging clerk works from a different side of the divider 49. The cashier directs the merchandise to one bagging clerk or the other by alternately setting the deflector 50 to the positions shown in Figure 2.

It has been found by experience that a cashier can ring up merchandise faster than one bagging clerk can arrange it in bags. Consequently, where there is only one bagging clerk to a check-out counter, the cashier must wait until the bagging clerk catches up with her, and the wait in line is thereby prolonged. The present invention overcomes this difficulty by providing for the direction of merchandise to two bagging clerks at each counter. The work of the cashier is also speeded up since she is not required to pull or drag the merchandise to a position where she can manipulate it for ringing up. Instead she merely depresses the pedal 18 to operate the belt 9 as required. Each article, on being rung up, is merely slid across the plate 36 to the discharge belt 12.

In the modification shown in Figures 11 and 12, the delivery belt 60 is passed around a drive roller 61 and a rear roller 62 at a lower level. Between

the two rollers is an idler roller 63 nearer the roller 62 and having a common horizontal tangent with the roller 61. Thus, the major portion of the upper lap of the belt is horizontal but provides a sloping portion 64 between the rollers 63 and 62. This portion furnishes a drop for the merchandise from the belt to the floor 65 over the sloping metal plate 66 that bridges the gap between the belt and the floor. As a result there is no binding or catching of merchandise in this area.

These figures also show a preferred form of deflector mechanism. The partition 67 thereof is pivoted at 68 to the floor 65 near the rear edge. To the forward end of the partition is joined the deflector by a simple horizontal hinge 69 to follow adjustment of the floor as previously described. The deflector comprises two sections 70 and 71 fastened together at an angle, near the roller 63, by a tie plate 72 and bolts 73. In one position at least, the deflector runs along a side of the frame structure without crossing the belt 60 and leaves the entire belt exposed, with an unreduced passage to the floor 65. In the other position of the deflector, the unavoidable restriction of the passage is considerably less than in the full line position in Figure 2.

Although specific embodiments of the invention have been illustrated and described, it will be understood that any alterations may be made without departing from the scope of the invention as indicated by the appended claims.

What I claim is:

1. In a checkout counter, a support, a pair of conveyors alined thereon horizontally with each other, a fixed bridging plate between said conveyors, means for driving one of said conveyors continuously, a receiving floor at the discharge end of the first named conveyor, a partition dividing the surface of said floor into two areas, a pivotally mounted deflector attached to said partition and extending to said plate, and operator controlled means for driving the other conveyor.

2. In a checkout counter, a support, a pair of conveyors alined thereon horizontally with each other, a fixed bridging plate between said conveyors, means for driving one of said conveyors continuously, a receiving floor at the discharge end of the first named conveyor, a partition dividing the surface of said floor into two areas, a pivotally mounted deflector attached to said partition and extending to said plate, an idler for establishing a driving connection from the first conveyor to the other conveyor, and operator actuatable means for controlling the engagement of said idler with said conveyors.

3. In a checkout counter, a support, a pair of conveyors alined thereon horizontally with each other, a fixed bridging plate between said conveyors, means for driving one of said conveyors continuously, a receiving floor at the discharge end of the first named conveyor, a partition dividing the surface of said floor into two areas, said floor being wider than said conveyors, a deflector hinged to said partition and extending to said plate, and operator controlled means for driving the other conveyor.

4. In a checkout counter, a support, a pair of conveyors alined thereon horizontally with each other, a fixed bridging plate between said conveyors, means for driving one of said conveyors continuously, a receiving floor at the discharge end of the first named conveyor, a partition di-

viding the surface of said floor into two areas, said floor having one edge alined with one edge of said conveyors and being widened from the other edge of said conveyors, a deflector hinged to said partition and extending to said plate, and operator controlled means for driving the other conveyor.

5. In a checkout counter, a support, a pair of conveyors alined thereon horizontally with each other, a fixed bridging plate between said conveyors, means for driving one of said conveyors continuously, a receiving floor hinged at the discharge end of the first named conveyor, a partition dividing the surface of said floor into two areas, a pivotally mounted deflector attached to said partition and extending to said plate, and operator controlled means for driving the other conveyor.

6. In a checkout counter, a support, a pair of conveyors alined thereon horizontally with each other, a fixed bridging plate between said conveyors, means for driving one of said conveyors continuously, a receiving floor at the discharge end of the first named conveyor, a partition dividing the surface of said floor into two areas, a pivotally mounted deflector attached to said partition and extending to said plate, said deflector being angular and formed to lie, in one position, alongside one edge of said first conveyor, and operator controlled means for driving the other conveyor.

7. In a checkout counter, a support, a pair of conveyors alined thereon horizontally with each other, a fixed bridging plate between said conveyors, means for driving one of said conveyors continuously, a receiving floor hinged at the discharge end of the first named conveyor, a partition dividing the surface of said floor into two areas and pivotally mounted on said floor, a deflector attached to said partition and extending to said plate, said deflector being angular and formed to lie, in one position, alongside one edge of said first conveyor, and operator controlled means for driving the other conveyor.

8. In a checkout counter, a support, a pair of conveyors alined thereon horizontally with each other, a fixed bridging plate between said conveyors, means for driving one of said conveyors continuously, a receiving floor slightly below the discharge end of the first named conveyor, said conveyor having a portion sloping downward toward said floor, a sloping bridging plate between said portion and said floor, and operator controlled means for driving the other conveyor.
